UNITED STATES PATENT OFFICE.

STEVEN SZALKAY, OF FLINT, MICHIGAN.

SHIELD.

1,110,084.

Specification of Letters Patent.

Patented Sept. 8, 1914.

Application filed February 10, 1914. Serial No. 817,893.

To all whom it may concern:

Be it known that I, STEVEN SZALKAY, a subject of the King of Hungary, residing at Flint, in the county of Genesee and State of Michigan, have invented certain new and useful Improvements in Shields, of which the following is a specification.

My invention relates to improvements in shields to be used as armor or protection for soldiers while in battle, and is designed to provide a portable device which may be handled and transported with facility, and quickly set up and put into use, and with equal facility be packed and ready for transportation.

The primary object of the invention is to provide a shield which will deflect the steel jacketed bullets of modern shoulder firearms, which is comparatively light, and jointed so that it may be folded up into compact form for transportation, and which may be quickly folded up and re-located during the advance of an attacking party in a battle. The shield is designed to act as a covering or a partial covering for the soldier, and is provided with openings or ports from which the soldier may fire upon the enemy, and at the same time the walls of the shield are so arranged as to upwardly deflect any striking bullets, and guide them away from the soldier in proximity to the armor, thus eliminating the possibility of the nearby soldier being struck by a bullet glancing from the shield or armor.

The invention consists in a metal shield constructed of sections suitably hinged together, and adapted to be set up or folded into compact form, and in a novel arrangement of the walls of the shield, as will be hereinafter set forth and claimed.

In the accompanying drawings I have illustrated one complete example of the physical embodiment of my invention constructed according to the best mode I have so far devised for the practical application of the principles of the invention.

Figure 1 is a perspective view from the front showing the shield erected for use. Fig. 2 is a plan view of the inside of the shield showing the sections flattened out. Fig. 3 is a perspective view of the shield with the sections compactly folded together for transportation. Fig. 4 is a detail view showing the manner of interlocking two plates or two thicknesses of the shield.

In the preferred embodiment of my inven-

tion, as shown in the drawings, the shield is constructed of light hard steel ground to give it a smooth even surface, and the shield as illustrated in the drawings weighs approximately thirteen or fourteen pounds, and will thus be understood to be easy of handling and manipulation.

The shield comprises eight sections 1, 1^a, 2, 2^a, 3, 3^a, 4, and 4^a, the sections 1, 1^a and 2, 2^a forming one side while the sections 3, 3^a, and 4, 4^a provide the other side of the shield. The two sides are hinged together as shown at 5, while each section is hinged to its adjoining section by means of the hinges 6 and 7. All of the hinge plates 8 are secured to the metal of the shield by means of welding or rivets, and the sections are adapted to fold on the line of these hinges so that the shield may be compactly packed, as in Fig. 3.

In Fig. 1, the shield is shown as set up, and it will be seen that the triangular sections provide a rearwardly and upwardly slanting corner or edge 9, from which the sides spread out in fan shape. The sections 2 and 3 are each provided with a port hole 10 through which the soldier or soldiers behind the shield may fire upon the enemy. In Fig. 1, it will be seen that the converging lines of the shield toward the upper point 11 will cause all striking bullets to be deflected upwardly and thus eliminate the menace or danger to surrounding soldiers. If desired, it will be readily understood that the sections 1 and 4, in Fig. 1, may be folded back, or swung in toward each other on their hinges 8, so that the soldier may be more completely incased, and in some instances this will be desirable and preferable.

I also use springs 14 in connection with the hinge joints to assist in spreading and holding the plates or sections in alined position.

While the weight of the shield ordinarily will be sufficient to hold the shield upon the ground, as shown, it is sometimes desirable that the shield be anchored to the ground. For this purpose I employ metal stakes as indicated at 12, which have bent ends hinged at 13 to some of the sections. When these stakes are driven into the ground, it will be apparent that the shield is firmly and securely held and will be difficult of dislodgment. The shield or armor is of metal approximately sixteen one-hundredths of an inch thick, and is approximately about eighty inches from front to rear, forty

2
inches wide, and has a height of about two feet. I do not, however, limit myself to the dimensions given as it will of course be understood that the size of the shield may be increased or diminished as required.

5 While I have illustrated the shield comprising eight sections, or coupled plates, it will be understood, of course, that I may employ a lesser number of sections at each 10 side of the shield. Two, for instance, could be used at each side of the center line in Fig. 1, and the shield thus composed could be folded as usual, but the packet would be much larger than the packet indicated in 15 Fig. 3. The sections can be joined by hinged members, and I contemplate attaching the hinged members to the sections either by electrically welding the coupling members to the sections, or by riveting the members. 20 In either event the outer surface of the shield when set up presents a perfectly smooth face against which an impinging bullet may strike and be deflected.

In Fig. 4 I show a modified form of the

invention embodying two plates as 20 and 25 21 which are locked together by means of the key 22 carried by the plate 20 which is passed through the slot 23 in the plate 21. In this manner when I employ two plies to the shield the plates or plies are locked together. 30

Having thus fully described my invention, what I claim as new, and desire to secure by Letters Patent, is:

A foldable portable metallic shield having 35 two triangular sides hinged together at an angle and supported on the lower edge of said sides, said shield having a porthole at the apex of the angle, and each side of the shield comprised of a series of hinged triangular sections, whereby the shield may be 40 folded into compact form.

In testimony whereof I affix my signature in presence of two witnesses.

STEVEN SZALKAY.
